UNITED STATES PATENT OFFICE.

HENRY H. NORRINGTON, OF WEST BAY CITY, MICHIGAN.

INKING-PAD.

SPECIFICATION forming part of Letters Patent No. 653,965, dated July 17, 1900.

Application filed January 19, 1900. Serial No. 1,983. (No model.)

To all whom it may concern:

Be it known that I, HENRY H. NORRINGTON, a citizen of the United States, residing at West Bay City, county of Bay, State of Michigan, 5 have invented a certain new and useful Improvement in Inking-Pads; and I declare the following to be a full, clear, and exact description of the invention, such as will enable others skilled in the art to which it appertains 10 to make and use the same, reference being had to the accompanying drawings, which form a part of this specification.

My invention has for its object an improved inking-pad; and it consists of the 15 construction, combination, and arrangement of devices hereinafter specified and claimed, and illustrated in the accompanying drawings, in which—

Figure 1 is a view in longitudinal section 20 illustrating features of my invention. Fig. 2 is an inverted plan view, the case being removed. Fig. 3 is a similar view showing a modification. Fig. 4 is a vertical longitudinal section thereof. Fig. 5 is a view in cross- 25 section on the line 5 5, Fig. 1. Fig. 6 is a view in cross-section on the line 6 6, Fig. 4. Fig. 7 is a view in perspective of another modification, the cover being in open position. Fig. 8 is a longitudinal vertical section 30 on the line 8 8, Fig. 7. Fig. 9 is a detail plan view showing another modified form of construction. Fig. 10 is an inverted detail plan view showing another form of construction. Fig. 11 is a section on the line 11 11, 35 Fig. 10. Fig. 12 is a view in section on the line 12 12, Fig. 8. Fig. 13 is an end view showing a plate and one manner of engaging the absorbent material therebeneath, together with a support therefor. Fig. 14 is a 40 view of a plate in side elevation with strips of absorbent material engaged therewith. Fig. 15 is a longitudinal section of portions of the device, illustrating another modification.

My invention aims more particularly to 45 provide a self-feeding inking-pad, so constructed and arranged that the pad will continuously supply itself with ink by suitable means, as hereinafter set forth.

I carry out my invention as follows:

A suitable case forming a receptacle or box is indicated at *a*, which may be provided

with a cover *b*. Within the receptacle is located an ordinary inking-pad *c*, constructed in any suitable manner. Underneath the 55 pad *c* and forming a support therefor is a plate *d*, constructed in any suitable manner, to permit ink passing therethrough into the pad *c*. To this end the said plate may be perforated or slotted or provided with holes 60 in any other manner, as may be desired. In the form shown in Figs. 1 to 6 and Figs. 9 and 14 said plate is formed with one or more slots or orifices, (indicated at *d'*.) In other figures a foraminous plate is shown.

As shown in Figs. 1 to 6, the plate may be 65 constructed of wood or other suitable material, resting upon the base of the receptacle *a*. If the plate is made foraminous, it may be made of sheet metal or other suitable material and be supported in any suitable manner above the base of the receptacle or box *a*, thereby forming a chamber *e* within the box beneath the plate, as shown in Fig. 8. An absorbent material or fabric of any desired 70 construction is indicated at *f*. This may consist of a piece of porous felt or wicking or any other material adapted to absorb ink and feed it to the inking-pad. Where the plate *d* rests upon the base of the receptacle the absorbent material or fabric *f* may have a portion 75 extending through the slot or slots formed in said plate, as indicated more particularly in Figs. 1 to 6 and in Figs. 9 and 14, the body of the absorbent fabric being located upon the 80 plate and underneath the inking-pad, the portion extending through the slot or slots of the plate being arranged to absorb the ink within the receptacle and feed the ink into the body of the absorbent fabric, where it will be readily absorbed into the inking-pad. In this 85 construction the marginal edges of the plate *d* may be undercut or set inward from the adjacent wall of the case of the receptacle, as indicated, for example, at *d'*, or the plate 90 may be beveled toward one extremity, as indicated at *d''*, affording a chamber or channel within the receptacle through which ink may pass, the plate being also formed with a channel *d'*, leading back to the slot *d'*. In this 95 case the slot *d'* may be formed intermediate the edges of the plate, the ends projecting through the slots or orifices of the plate being indicated at *f'*.

5 The plate d , if made of foraminous metal, may be supported within the receptacle, as by a marginal frame (indicated at g in Fig. 8 and in dotted lines in Fig. 9) located adjacent to three sides of the receptacle, or supporting blocks or strips h may be secured to the plate intermediate its edges and adjacent to the absorbent material or fabric f , as shown in Figs. 10 and 11.

10 In the form shown in Figs. 8, 10, and 11 the absorbent material is shown located within the chamber e , resting upon the base of the receptacle and contacting with the under surface of the foraminous plate. As shown in 15 Fig. 13, however, an absorbent strip or wick (indicated at i) may be employed engaged upon a longitudinal supporting-strip j , the edges of the strip or wick extending downward over the sides of the strip j to the base 20 of the chamber e to act as a feeder to carry the ink to the pad c .

In the form shown in Fig. 14 the foraminous plate d is provided with the slot or slots d' , above mentioned, the strips of absorbent material f being turned through said slots, the extremities of the slots projecting downward into the chamber e to act as a wick or feeder. In this form of construction a portion of the absorbent material is engaged upon the upper side of the foraminous plate and in contact with the pad c , the ends of the absorbent material projecting through the slots to the base of the chamber e , as where a wooden slotted plate is employed.

30 At one end of the receptacle is formed an ink-well k , opening through a suitable orifice (indicated at l) into the base of the receptacle. The ink-well is formed with a cover m made in the form of a slide, the cover being formed 35 with a depending flange, (indicated at n .) The cover may be provided with a turned edge at one end, (indicated at q .) whereby it may be conveniently handled and reciprocated. The flange n is at the inner portion of the cover 40 and is so constructed that when the cover is pulled out for filling the well the slide will cover the orifice l , closing said orifice; but when the cover is pushed into normal position the flange n will leave said orifice open to permit the ink to feed from the ink-well into the receptacle a . The flange n acts as a valve to close the orifice l when the cover is pulled out, leaving the orifice free when the cover is in normal position. It will be thus observed 45 that when the ink-well is filled with ink the ink will be free to pass into the receptacle a , where it will be absorbed by the absorbent material located therein or projecting thereinto. The absorbent material having absorbed the ink will, obviously, permit the ink to be readily absorbed into the inking-pad c to keep said pad perpetually supplied with ink, it only being necessary occasionally to replenish the ink-well k to keep the inking-pad suitably moistened with ink. The absorbent material obviously prevents the ink

from remaining in a free condition within the receptacle, where it would be liable to splash about or be spilled in handling the pad. Moreover, in striking the pad with a stamp to ink it there is no liability of splashing the ink, as might be the case were it not for the absorbent material.

Where a support underneath the plate is located intermediate its edges, I prefer that the support should have a fixed engagement with the plate.

In the form shown in Fig. 15 the support may consist of a block or piece j , fastened to the under side of the foraminous plate and secured to the bottom of the receptacle by a fastening device r , passed upward therethrough from the bottom of the receptacle. The support, if employed, may consist of wood, located under the center of the foraminous plate or plural supports may be employed, located toward opposite ends of said plate; but I do not limit myself to any particular manner of supporting the plate within said receptacle, nor do I limit myself solely to the use of a support, as my invention embodies particularly the location of absorbent material underneath the pad to feed ink to the pad.

Where a plate is slotted intermediate its edges to receive the absorbent material, as shown in Figs. 3, 4, and 6, the end of the plate adjacent to the ink-well may be cut away, as shown at d^3 , to permit the flow of ink from the well into the receptacle and through the channel d^4 to the absorbent material. Where a plate resting upon the base of the receptacle is not made to fit closely therein, an additional plate (indicated at t) may be employed, as shown in Figs. 1 and 5, intervening between the plate and the inking-pad to more effectively support said pad.

What I claim as my invention is—

1. In an inking-pad, the combination of a receptacle, a plate channeled on its undersurface and formed with an opening therein communicating with said channel, a pad above said plate, absorbent material having a portion thereof projecting through the opening of the plate to feed the ink to the pad, and means to feed the ink into said channel.

2. In an inking-pad, the combination of a receptacle, a plate formed with an opening therein, a pad above said plate, absorbent material to feed ink through said opening to said pad, an ink-well opening into said receptacle, and means to control the feed of said ink-well, said plate provided with a channel on its under surface through which ink may be conducted from the ink-well to the opening in said plate.

3. In an inking-pad, the combination of a receptacle, a plate formed with an opening therethrough within the receptacle, absorbent material extending beneath said plate, and an ink-well to feed ink to said absorbent material, a sliding cover for said ink-well, said

cover provided with a depending flange to close said communication when the cover is in open position.

4. In an inking-pad, the combination of a receptacle, a plate, a pad located upon the plate, absorbent material extending beneath said plate to feed ink to said pad, an ink-well communicable with the receptacle underneath the plate, and a sliding cover for said ink-well, said cover formed with a depending flange to close communication of the well with the receptacle when the cover is in open position.

5. In an inking-pad, the combination of a receptacle, an ink-well to feed ink to said receptacle, and a sliding cover for said ink-well, said cover provided with a depending flange to close communication between the ink-well and the receptacle when the cover is in open position. 15

In testimony whereof I sign this specification in the presence of two witnesses.

HENRY H. NORRINGTON.
